JAMES AUSTIN TOOLEY, OF STAMFORD, NEW YORK.

STEAM-ENGINE.

SPECIFICATION forming part of Letters Patent No. 787,134, dated April 11, 1905.

Application filed June 9, 1904. Serial No. 211,804.

To all whom it may concern:

Be it known that I, JAMES AUSTIN TOOLEY, a citizen of the United States, and a resident of Stamford, in the county of Delaware and 5 State of New York, have invented a new and Improved Steam-Engine, of which the following is a full, clear, and exact description.

The object of the invention is to provide a new and improved steam-engine of the compound type arranged to utilize the steam in the high-pressure cylinder approximately under boiler-pressure to insure a quick passage of the exhaust-steam from the high-pressure cylinder to the low-pressure cylinder and to 15 utilize the steam in both cylinders to the fullest advantage.

The invention consists of novel features and parts and combinations of the same, as will be more fully described hereinafter and then 20 pointed out in the claims.

A practical embodiment of the invention is represented in the accompanying drawings, forming a part of this specification, in which similar characters of reference indicate corresponding parts in all the views.

Figure 1 is a side elevation of the improvement, parts being in section. Fig. 2 is a transverse section of the same on the line 2 2 of Fig. 1. Fig. 3 is a plan view of the same, the 30 casing being indicated in dotted lines. Fig. 4 is a sectional plan view of the high-pressure cylinder and the steam-inlet; and Fig. 5 is a sectional side elevation of the cam-lever for operating the valves in the low-pressure cylinder, the section being on the line 5 5 of Fig. 2.

As illustrated in Fig. 1, two compound steam-engines are arranged tandem on the engine-frame A, and the said engines are connected with the main shaft B, journaled in suitable bearings carried on the engine-frame. It is, however, understood that I do not limit myself to the arrangement described, as a single compound engine only may be used, or, if 45 desired, more than two may be used. As the two compound engines shown are alike in construction it suffices to describe but one in detail. The high-pressure cylinder C of the engine is in axial alinement with the low-pressure 50 cylinder D, and in the said cylinders C and D

reciprocate pistons E and E', respectively connected with each other externally by side rods E² and a cross-bar E³, of which the latter is rigidly connected at its middle with the piston-rod E⁴ of the high-pressure-cylinder piston E, and the side rods E² are rigidly connected with the piston E' of the low-pressure cylinder D. The piston E has no rod, it will be observed, and is directly connected by a pitman F with a crank-arm B' on the main 60 shaft B, so that when the engine is running the two connected pistons E and E' travel in unison. The low-pressure cylinder D is fixed on the engine-frame A, while the high-pressure cylinder C is mounted to slide in the direction of its length in a bearing G, fixed on the engine-frame A. The high-pressure cylinder C is open at both ends, and through the upper open end extends the piston-rod E⁴, while the lower portion or working end of the said 65 cylinder extends through a chamber H, into which opens a steam-supply pipe I, connected with a boiler or other suitable source of steam-supply and provided with a suitable admission-valve I' under the control of the engineer for 70 turning on or shutting off the steam whenever it is desired to start or stop the engine, it being noted that the walls of said chamber H are practically integral extensions of the 75 said bearing G. The lower end of the cylinder C is provided exteriorly with an annular integral valve C', adapted to be seated on a seat H', formed in the chamber H between the steam-inlet pipe I and the extreme lower end of the chamber, so that when the cylinder 80 C is in a lowermost position, as illustrated in Fig. 2, then live steam from the pipe I can pass by way of the chamber H and the open valve-seat H' into the lower end of the cylinder C to act on the piston E therein to push 85 the same in an upward direction. When the piston E reaches the end of its upward stroke, then the high-pressure cylinder C is shifted bodily, as hereinafter more fully described, to move the valve C' onto the seat H' to shut 90 off the live steam from the working end of the high-pressure cylinder C. Communication is established between the working end 95 of the high-pressure cylinder C and the upper or working end of the low-pressure cyl- 100

inder D, so that the exhaust-steam from the high-pressure cylinder C can readily pass into the working end of the low-pressure cylinder D at the time the pistons E and E' begin their 5 downward stroke, and for this purpose the upper end of the low-pressure cylinder D is provided with a head D', having a channel D² leading from the upper end of the low-pressure cylinder to the lower end of the high-pressure cylinder C and also to the lower end 10 of the chamber H. In this channel D² is arranged an outlet-channel D³, said channels being controlled, respectively, by an inlet-valve J and an exhaust-valve K, the said outlet-15 channel connecting with the exhaust-pipe D', leading to the outer air. The valves J and K operate in unison in such a manner that when one moves to its seat the other moves off its seat; and for this purpose the valves have 20 their stems J' and K' pivotally connected by links J² and K² with a lever L, fulcrumed at L' on the bearing G, as plainly indicated in Fig. 3. Springs J³ and K³ are interposed between the lever L and the links J² K², so 25 as to yieldingly hold the valves J and K to their seats in the channels D² and D³. The lever L is pivotally connected with the upper end of a rod L², provided at its lower end with a cross-bar L³, fitting into the groove N' of a 30 cam-lever N, fulcrumed on a pin N², secured to the lower end of the cylinder D. The cam N is provided with a friction-roller N³, engaging a cam-groove O' in a cam O, secured on an auxiliary shaft P, journaled 35 in suitable bearings on the engine-frame A, and on the said shaft P is secured a gear-wheel P', in mesh with a gear-wheel P², attached to the main shaft B, so that when the latter is rotated a rotary motion is given by 40 the gear-wheels P² and P' to the shaft P to rotate the latter in unison with the main shaft B. For each revolution of the shaft P the cam-lever N is rocked from one side to the other, so that a swinging motion is given to the lever 45 L, to alternately open and close the valves J and K in unison with the movements of the pistons E and E', so that when the pistons E and E' are on the upstroke the valve K is opened 50 for the exhaust-steam in the low-pressure cylinder D to pass out by way of the channel D³ and during this time the valve J is closed and the valve C' is off its seat H'. When the pistons E and E' reach the end of their upward stroke the cylinder C is shifted to move the 55 valve C' onto its seat H' to shut off the live steam from the cylinder C, and then the valves J and K are reversed—that is, the valve J is opened while the valve K is closed, so that the exhaust-steam from the high-pressure cylinder C can now pass by way of the open channel D² into the working end of the low-pressure cylinder D, to force the piston E' 60 downward therein by the expansive force of the steam. When the pistons E and E' reach 65 the end of their downward strokes, then the

valves J and K are again reversed—that is, the valve J is closed and the valve K is opened and at the same time the high-pressure cylinder C is shifted to move the valve C' away from the seat H' to allow live motive agent 70 to pass from the chamber H, approximately under boiler pressure, into the working end of the cylinder C to push the piston E therein upward, and as the pistons E and E' are rigidly connected with each other the piston 75 E' also moves in an upward direction.

In order to shift the cylinder C in the manner above described, the following device is provided: From the upper end of the high-pressure cylinder C extend lugs C', on which 80 is fulcrumed a lever Q, mounted to swing at its rear end at Q' in a bearing A', forming part of the engine-frame A. The forward or free end of the lever Q is pivotally connected with a rod R, extending downwardly and carrying at its lower end a cross-pin R', engaging a V-shaped slot N⁴, formed in the cam-lever N previously referred to, the slot N⁴ being adjacent to the slot N', in which operates the pin L³, as previously described. 90

The rod R is preferably made in two parts R² and R³, of which the part R³ carries the pin R', and the said part R³ is provided with a casing R⁴, in which the lower end of the part R² is mounted to slide. A spring R⁵ is 95 arranged in the casing R⁴ and presses against a collar R⁶ held on the part R², so as to yieldingly connect the parts R² and R³ with each other to allow easy working of the rod R on the cam-lever N, swinging from side to side 100 when the machine is running. By the arrangement described sudden jars of the cylinder C are prevented to permit easy seating of the valve C' on the seat H'. When the machine is running, the cam-lever N is caused 105 to swing sidewise by the action of the cam O, so as to impart an up-and-down movement to the rods L² and R, to actuate the levers L and Q for alternately opening and closing the valves J and K and shifting the cylinder C in 110 the direction of its length to move the valve C' onto its seat H' or off the said seat.

In order to permit of reversing the engine, the pins R' and L³ are shifted simultaneously 115 from one side of their slots N' and N⁴ to the other side thereof, and for this purpose the following device is provided: In the arrangement shown the two rods R for the two engines are connected with each other by a link R⁷, and a link L⁴ connects the two rods 120 L² with each other. One of the connected rods R is pivotally connected by a link S (see Fig. 1) with a rack S', mounted to slide in suitable bearings attached to the engine-frame A. The rack S' is in mesh with a pinion S², secured on a shaft S³, extending transversely and journaled in suitable bearings carried on the engine-frame A. On the shaft S³ is secured a hand-wheel S⁴, provided with a handle S⁵ and with a pin S⁶, located diamet- 125

rically opposite the handle S^5 , as plainly indicated in Fig. 1. The pin S^6 is adapted to engage a notch T' , formed in a disk T , secured on a shaft T' , journaled in suitable bearings on the engine-frame A , and on the peripheral face of the said disk T is formed a notch T^3 , adapted to be engaged by a spring-dog T^4 for normally locking the disk T against rotation. On the shaft T^2 is secured an arm U , connected by a link U' with a lever U^2 , fulcrumed on the engine-frame, and connected by a link U^3 with one of the connected rods L^2 , employed for working the valves J and K , as before explained. The link U^3 is provided with a pivoted arm U^4 , drawn on by a spring U^5 , attached to a link U^6 , fulcrumed on the engine-frame, so as to normally hold the link U^3 in an uppermost position. When the engine is running forward, the pins L^3 and R^7 are in the right-hand sides of their slots N' and N^4 , and when it is desired to reverse the engine the operator turns the hand-wheel S^4 in the direction of the arrow a' by taking hold of the handle S^5 to move the pin S^6 in engagement with the notch T' to turn the disk T in the direction of the arrow b' . On turning the hand-wheel S^4 the shaft S^3 and with it the pinion S^2 are rotated to impart an outward sliding motion to the rack S' , which by the links S and R^7 imparts a simultaneous sidewise swinging motion from the right to the left to the rods R to shift the pins R' from the right-hand side of the slot N^4 to the left-hand side thereof to cause a reversal of the movement of the cylinder C in its bearing G . At the same time the rotation of the disk T in the direction of the arrow b' causes the arm U to swing inward, so that the link U' imparts a swinging motion to the lever U^2 , which by the links U^3 L^4 imparts a swinging motion to the rods L^2 of the two engines to move the pins L^3 of the said rods from the right-hand side of the slot N' to the left-hand side thereof to reverse the valves J and K .

In order to insure an easy running of the engine, the entire machine is inclosed in a suitable casing A^2 , attached to the engine-frame A , and the lower portion of the said casing is filled with oil or other suitable liquid lubricant to keep the main shaft and adjacent parts properly lubricated at all times.

The operation is as follows: When the several parts are in the position illustrated in Fig. 2, then the piston E in the high-pressure cylinder C is forced upward by the pressure of the live steam passing from the supply-pipe I , chamber H , and valve-seat H' into the working end of the high-pressure cylinder C , and at the same time the exhaust-steam in the upper or working end of the low-pressure cylinder D passes out by way of the open valve K and channel D^3 to the exhaust-pipe D^4 .

When the pistons E and E' have reached the end of their upstrokes, then the position of

the valves J and K is reversed by the action of the cam O , lever N , rod L^2 , and lever L , and at the same time the high-pressure cylinder C is caused to slide upward to move its valve C' on the seat H' to shut off the live steam from the working end of the high-pressure cylinder C . The upward movement of the high-pressure cylinder C is accomplished by the cam O , lever N , rod R , and lever Q at the same time that the valves J and K are reversed. The exhaust-steam in the lower or working end of the high-pressure cylinder C now passes by way of the channel D^2 into the upper or working end of the low-pressure cylinder D to act on the piston E' therein to force the same downward by the expansive force of the steam. As the piston E is connected with the piston E' , it is evident that the piston E now moves on its down or inward stroke to insure a complete exhaust of the motive agent from the high-pressure cylinder C . When the pistons E and E' have reached the end of their downstrokes, then the valves J and K are again reversed, and the cylinder C is caused to slide downward, so that the valve C' moves off its seat H' to again admit live steam to the lower or working end of the cylinder D , and as the valve J is now closed and the valve K is open it is evident that the force of the live steam is exerted against the piston E to push the same upward, while the exhaust-steam in the low-pressure cylinder D passes out of the same by way of the open valve K , as previously explained.

When using two or more engines tandem, as described, the crank-arms B' on the main shaft B are set at angles one to the other, so that the live motive agent is almost always active in one of the high-pressure cylinders.

From the foregoing it will be seen that the live steam enters the high-pressure cylinder almost at boiler-pressure, and the passage of the exhaust-steam from the high-pressure cylinder to the working end of the low-pressure cylinder is of such short duration as to insure utilization to the fullest advantage of the motive agent in both the high and low pressure cylinders. By the operator turning the hand-wheel S^4 more or less the pin R' in the slot N^4 can be shifted nearer to or farther from the middle or apex of the slot N^4 , so that the cam-lever N imparts less or more up-and-down movement to the rod R to slide the cylinder C less or more in its bearing, and hence holding the valve C' seated longer or shorter on its seat H' to admit less or more steam to the high-pressure cylinder. It is understood that by having the cushioning device in the two-part rod R the valve C' is always moved to its seat H' and is only pulled off its seat by the action of the cam-lever N on the pin R' , and the duration the valve is off its seat is governed by the position of the pin R' in the slot N^4 . The slot N^4 for the pin L^2 is straight,

and hence the opening and closing of the valves J and K are regular, and as the slight turning of the hand-wheel S⁴ for shifting the pin R' in either side of the slot N⁴ does not affect the disk T it is evident that the pin L³ always occupies one end of its slot N' and is only shifted from one side of the slot to the other when the engine is reversed. By reference to Fig. 1 it will be seen that moving the handle S⁵ downward to a lowermost position causes only shifting of the pin R' in the slot N⁴, but does not affect the position of the pin L³ in the slot N', as the pin S⁶ is then still inactive relative to the disk T. When the handle S⁵ is in a lowermost position, the pin R' stands in the middle of the slot N⁴ and the cylinder is practically at a standstill and in a closed position and the live steam is shut off. A further turning of the handle S⁵ in the direction of the arrow a' reverses the engine.

Although I have shown and described the invention as a steam-engine, it is evident that other motive agents capable of doing work by their expansive force may be used.

Having thus described my invention, I claim as new and desire to secure by Letters Patent—

1. A compound engine having a high-pressure cylinder movable in the direction of its length, a steam-supply for one end of the cylinder, controlled by the high-pressure cylinder, a low-pressure cylinder in axial alignment with the high-pressure cylinder, pistons movable in said cylinders, and a connection between the pistons to cause them to move in unison.

2. A compound engine having a high-pressure cylinder movable in the direction of its length, a steam-supply for one end of the cylinder, a valve at the end of the cylinder for controlling the steam-supply, a low-pressure cylinder, a piston therein, and valves for controlling the flow of the exhaust-steam from the high-pressure cylinder to the said low-pressure cylinder.

3. A compound engine having a high-pressure cylinder movable in the direction of its length, a piston therein, a steam-supply for one end of the cylinder, controlled by the high-pressure cylinder, a low-pressure cylinder, a piston therein, valves for controlling the flow of the exhaust-steam from the high-pressure cylinder to the said low-pressure cylinder, and a connection between the said pistons in the high and low pressure cylinders, for the pistons to move in unison.

4. A compound engine having a high-pressure cylinder movable in the direction of its length, a chamber surrounding one end of the cylinder and provided with a valve-seat, a steam-supply communicating with said chamber, a valve on said cylinder for controlling the passage of the steam-supply from said chamber to the said end of the cylinder, means for imparting movement to the said high-

pressure cylinder to move the valve from and to its seat, and a low-pressure cylinder communicating with the high-pressure cylinder.

5. A steam-engine comprising a live-steam supply, a high-pressure cylinder having lengthwise movement and provided with means for opening and closing the said steam-supply to the open working end of the cylinder, a piston reciprocating in the said high-pressure cylinder, a low-pressure cylinder having its working end in communication with the said working end of the high-pressure cylinder, a piston in the low-pressure cylinder, a valve controlling the said communication, means for connecting the pistons with each other, a main shaft connected with the low-pressure piston, a valve-actuating device controlled from the said shaft, for operating the said valves in unison, and an actuating device for the said high-pressure cylinder, controlled from the said shaft.

6. A steam-engine provided with a cylinder mounted to slide, to control the admission of steam to the cylinder, a piston in the said cylinder, a main shaft, a cam driven from the said shaft, a cam-lever actuated from the said cam and provided with a slot, and an operating connection for the said cylinder and engaging the said slot.

7. A steam-engine provided with a cylinder mounted to slide, to control the admission of steam to the cylinder, a piston in the said cylinder, a main shaft, a cam driven from the said shaft, a cam-lever actuated from the said cam and provided with a slot, and an operating connection for the said cylinder and engaging the said slot, the said connection having a cushioning member.

8. A steam-engine comprising a live-steam supply, a high-pressure cylinder having lengthwise movement and provided with means for opening and closing the said steam-supply to the open working end of the cylinder, a piston reciprocating in the said high-pressure cylinder, a low-pressure cylinder having its working end in communication with the said working end of the high-pressure cylinder, a piston in the low-pressure cylinder, a valve controlling the said communication, means for connecting the pistons with each other, a main shaft connected with the low-pressure piston, a valve-actuating device controlled from the said shaft, for operating the said valves in unison, an actuating device for the said high-pressure cylinder, controlled from the said shaft, and a reversing mechanism under the control of the operator, for reversing the said actuating devices for the valves and the high-pressure cylinder.

9. A steam-engine provided with a cylinder mounted to slide, to control the admission of steam to the cylinder, a piston in the said cylinder, a main shaft, a cam driven from the said shaft, a cam-lever actuated from the said cam and provided with a V-shaped slot, a rod

having a cross-pin engaging the said slot, a lever connecting the rod with the said high-pressure cylinder, and a manually-controlled reversing means for moving the pin end of the rod from one side of the slot to the other side of the slot.

10. An engine provided with a cam-lever having two slots, a valve-operating mechanism connected with one of the slots, and a high-pressure cylinder-actuating mechanism connected with the other slot.

11. An engine provided with a cam-lever having two slots, a valve-operating mechanism connected with one of the slots, a high-pressure cylinder-actuating mechanism connected with the other slot, and manually-controlled means for shifting the positions of the said mechanism in the said slots.

12. A steam-engine, comprising a steam-supply, a bearing, a chamber provided with a

valve-seat, and the walls of which are integral with said bearing, a high-pressure cylinder having lengthwise movement in the bearing, and formed with an integral annular valve co-operating with said seat for opening and closing the steam-supply to the working end of said cylinder, a piston in the latter, a low-pressure cylinder, a piston therein, connections between the said pistons to cause them to move in unison, and means for delivering the steam to said cylinders to effect the exhaust-stroke of one piston and the working stroke of the other.

In testimony whereof I have signed my name to this specification in the presence of two subscribing witnesses.

JAMES AUSTIN TOOLEY.
